UNITED STATES PATENT OFFICE,

TALBOT C. DEXTER, OF PEARL RIVER, NEW YORK, ASSIGNOR TO DEXTER FOLDER COMPANY, OF NEW YORK, N. Y., A CORPORATION OF NEW YORK.

PAMPHLET-FEEDING DEVICE FOR STAPLING-MACHINES.

1,010,124.

Specification of Letters Patent. Patented Nov. 28, 1911.

Application filed October 5, 1909. Serial No. 521,131.

To all whom it may concern:

Be it known that I, TALBOT C. DEXTER, a citizen of the United States, and resident of Pearl River, in the county of Rockland and State of New York, have invented certain new and useful Improvements in Pamphlet-Feeding Devices for Stapling-Machines, of which the following is a specification.

The present invention relates to an apparatus by which signatures or bunches of sheets, either with or without covers, are fed to suitable stapling machinery and automatically positioned to receive the required number of wire staples at predetermined points, to form books or pamphlets.

My improved machine comprises a suitable feed table, preferably in the form of an angular saddle upon which the successive signatures or bunches of sheets can be conveniently placed by an operator in position to be automatically carried forward by a step by step feeding operation to receive the binding staples, either at one operation as in the case of small pamphlets, or in successive operations as in the case of larger pamphlets, and suitable feeding mechanism for carrying the signatures or bunches of sheets through the said step-by-step feeding operation.

The improved pamphlet feeding mechanism includes a reciprocating feed slide mounted upon the feed table, a reciprocating rock shaft journaled adjacent to the table and carrying feed fingers adapted to intermittently and successively engage sheets against said feed slide, and means for imparting reciprocating and rocking motions to said rock shaft.

In order that my invention may be fully understood, I will first describe the same with reference to the accompanying drawings, and afterward point out the novelty more particularly in the annexed claims.

In the accompanying drawings: Figure 1 is an end elevation of my improved automatic pamphlet binding machine. Fig. 2 is a front elevation of the same. Fig. 3 is a detail plan view of part of the operating mechanism for the step by step feeding device. Fig. 4 is a detail perspective view of part of the same, looking from beneath the machine. Fig. 5 is a detail perspective view of part of the feed table or saddle and a part of the feeding mechanism which operates thereon. Fig. 6 is a vertical transverse sectional elevation of the machine

showing the automatically controlled clutch for operating the stitching machine. Fig. 7 is a detail plan view of the same. Fig. 8 is a view similar to Fig. 6 showing more of a detail view of the stitcher and operating mechanism. Fig. 9 is a detail front elevation of the feed table or saddle showing the successive positions of the pamphlet thereon with relation to the stitching machine and automatic trip. Fig. 10 is a similar view illustrating the position upon the feed table of pamphlets of larger size. Fig. 11 is a perspective view of the automatic clutch arranged between the stitching machine and its operating mechanism. Figs. 12 and 13 are detail views of the automatically controlled block for actuating the clutch of the stitching machine. Fig. 14 is a detail perspective view of one of the controlling cams of the automatic tripping device.

My improved machine is built upon a frame of suitable construction to properly support the several operative parts.

The frame generally is indicated by the reference letter A. Freely journaled in the bracket arms 1 projecting forwardly from upright portions of the frame A is the main power shaft 5 provided at one end with the fast and loose driving pulleys 6 and 7 over which operates the power belt 8 under the control of the manually actuated belt shipper 9. This belt shipper may be of any suitable construction, and as shown includes the foot lever 10 connected by link 11 with a bell crank lever 12 pivoted upon a bracket support 13 and connected at 14 with the rod 15 freely journaled in bearings of the machine frame and carrying the belt shipper 9.

The power shaft 5 carries the differential belt pulleys 20, 21 and 22 which are reversely arranged with respect to the differential belt pulleys 25, 26 and 27 mounted upon an auxiliary shaft 30 journaled in bracket bearings 31 of the machine frame. This auxiliary shaft 30 extends parallel with, and is arranged above, the power shaft 5. An endless belt 35 passes around corresponding pulleys upon the power shaft and auxiliary shaft, for driving the latter from the former at the required speed, the differential pulleys enabling the operator to regulate the speed of his machine to suit his requirements.

All of the several parts of the improved machine are operated from the auxiliary

shaft 30 through suitable gearing which will presently be explained. The various parts of the machine will be taken up in their order considering the operation of binding a pamphlet.

6 Mounted upon the upper part of the main frame of the machine along the rear side thereof, is the feed table 40 constructed of angular or saddle form as is customary in pamphlet binding machinery. As shown in 10 Fig. 2 of the drawings this feed table or saddle extends beyond the supporting frame at both ends of the machine to support the signatures or bunches of leaves throughout 15 the feeding and stapling operations.

15 45 is a gage finger suitably mounted upon one face of the feed table 40 at the left hand end of the machine as shown in Fig. 2, for the purpose of accurately indicating to 20 the operator the starting position upon the feed table for the signatures or unbound pamphlets.

25 50 is a longitudinally movable rock shaft freely journaled in bracket bearings 51 secured to the forward edge of the feed table 40 and extending parallel with the feed table and projecting beyond both ends of the feed table. This rock shaft 50 is capable of reciprocating longitudinally in its 30 bearings as well as rocking back and forth therein. Arranged at suitable distances apart along the rock shaft 50 are the feed fingers 55, fixed to the shaft 50 and each formed at its free end with a socket to hold 35 a friction pad 56 of rubber or other suitable material.

40 The forward face of the saddle or feed table 40 is slotted longitudinally as indicated at 60, and secured to the under side of the table parallel with the slot 60 is the slotted channel bar 61 in the channel of which reciprocates the bar or plate 62 arranged directly beneath the longitudinal slot 60 of the feed table or saddle. Sliding 45 in the slot 60 is a feed bar 65 which is secured to the bar 62 by screws 66 or other suitable means. Operating in the longitudinal slot 61 of the channel bar 61 is a block 67 attached to the under face of the bar or 50 plate 62 and having secured to it a plate 70 from which extends an arm 71 formed with a socketed end 72 through which extends the rock shaft 50. Upon opposite sides of the socketed end of arm 71 are arranged the adjustable collars 73 between which the arm 55 71 is confined to form an adjustable connection between the rock shaft 50 and the plate 70, and at the same time permit the free rocking of the shaft 50 in socket 72.

55 60 The plate 70 carries a downwardly presented bearing pin 75 upon which is pivoted at its elbow a bell crank lever 76. One arm of the bell crank lever 76 is connected through a rod or link 77 with a rock arm 78 65 adjustably secured to the rock shaft 50, said

rod or link 77 being pivotally connected at its opposite ends to the bell crank lever 76 and rock arm 78. The other arm 76^a of the bell crank lever 76 is presented between two adjustable stop pins or screws 80 threaded 70 through the ears or lugs 81 projecting beneath the plate 70. These stop pins or screws 80 are designed to limit the movement of the bell crank lever 76 upon the plate 70 to permit the rocking of the shaft 75 50 by the bell crank before imparting movement to the plate 70 and parts connected therewith. This arm 76^a of the bell crank 76 has pivoted to it at 85 a rod or pitman 86 which has an adjustable pivotal connection 80 87 at its other end with one slotted end 88 of a rocking lever 89 pivoted at 90 upon a bracket arm 91 secured to the machine frame. The opposite end of the lever 89 is slotted as shown at 92 to receive a crank pin 93 which is radially adjustable upon a crank disk 95 keyed to a shaft 96 journaled in the bearing bracket 97 of the machine frame. Keyed to the opposite end of the short shaft 96 is a gear wheel 98 which is driven by a train of gears 99, 100 and 101, the last named of which is keyed to the end of the short shaft 102 journaled in a bracket arm 103 and carrying at its opposite end a bevel gear 104 meshing with and driven by a similar bevel gear 105 which is keyed to the left hand end of the auxiliary shaft 30 above referred to.

55 It will be observed from the drawings that the rubber pads 56 carried by the feed fingers 55 are presented just above the feed plate 65 which operates in the slot of the feed table, so that when the pads of said feed fingers are moved into engagement with the feed bar 65 they will grip a signature or bunch of sheets against said feed bar, and move the same longitudinally of the feed table.

60 In proper position with relation to the feed table 40 I arrange a stapling or wire stitching machine of any suitable construction. My invention is not limited to any specific form of stitching machine proper, but for the purpose of explanation it may be stated that a machine such as disclosed in Patent No. 366,146 dated July 5th, 1887, 110 115 may be employed. I prefer to employ a machine which is capable of driving two wire staples at a single operation, although it will be understood that a single stapling machine or one which will drive a greater number of staples may be employed without departing from the spirit of my invention.

65 In the accompanying drawings I have not attempted to illustrate the detail construction of the stitching machine, but have 120 illustrated only enough of the machine to show the operation of my invention. The stitcher as shown includes a supporting bracket arm 110 upon which the oscillating member 111 is pivoted at 112 and actuated 130

by a link 113 pivoted thereto at one end 114 and at its opposite end to a crank stud 115 upon a cam disk 116. This cam disk 116 is keyed to a short shaft 117 journaled in a bearing 118 projecting from bracket 110. Cam disk 116 engages an anti-friction roller 120 carried by a lever 121 pivoted to the machine frame at 122 and projecting beneath the vertically sliding anvil stock 125 arranged beneath a suitable opening in the angle of the feed table 40 to be thrown up at the proper moment to coöperate with the stapling device 126 arranged above the feed table and actuated by the oscillating mem- 15 ber 111.

The short shaft 117 supporting the cam disk 116 also carries a gear wheel 130 in constant mesh with a gear wheel 135 freely journaled upon a shaft 136 mounted in 20 frame bearings 137 and driven by a large gear 138 keyed to said shaft and meshing with a pinion 139 keyed to the auxiliary shaft 30. To clutch the gear 135 upon the shaft 136 to cause the operation of the 25 stitching machine when a signature or pamphlet is in position to be stapled, I have provided an automatic clutching mechanism which is operated under the control of a controlling device supported in the path of 30 the pamphlets over the feed table. This mechanism will now be explained.

140 is a clutch ring supported by a yoke 141 upon a hub 142 which is keyed to the shaft 136 as shown at 143. This clutch ring 35 140 has pivotally mounted upon it at 145 a clutch hook 146 which is adapted to engage a clutch pin 150 projecting from the face of the gear wheel 135 into the clutch ring 140. A spring device 147 engages the 40 heel of the clutch hook 146 to retain it yieldingly into engaged position with the clutch pin 150.

The free end of the clutch hook 146 carries a laterally projecting pin 148 upon 45 which is mounted an anti-friction roller 149 with which the automatically controlled clutch actuating device engages to release the clutch. This operation is accomplished by the following mechanism. The feed table 50 40 is provided adjacent to the stapling machine with a slot 160 into which projects the lower end of a tripping finger 161 freely journaled at 162 upon a rod or bar 163 projecting from the bracket 110 to a point 55 above the feed table. A curved feeler arm 165 is mounted upon a rock shaft 166 and projects over the upper end of the tripping finger 161 in position to engage said tripping finger and be arrested thereby when 60 the tripping finger is in its normal position. The rock shaft 166 is journaled in a suitable bracket bearing and carries a rock arm 168 connected through a link 169 with a rock arm 170 keyed to a rock shaft 180 65 journaled in bracket bearings 181. Project-

ing upwardly from the rock shaft 180 is a long rock arm 182 having a slotted upper end as indicated at 183 in which engages a headed pin or bolt 184 seated in the block 185 secured to the ends of two rods or bars 186 and 187. These rods or bars 186 and 187 pass freely through bearings 188 and support at their opposite ends a cam block 189 which is adapted to be projected into the path of the anti-friction roller 149 upon the clutch hook above referred to for disengaging the clutch which operates the stapling machine. This long rock arm 182 has mounted upon it, between its ends, an anti-friction roller 195 which is held normally in 70 engagement with the face cam 196 by means of a spring actuated rod 197 connected with said rock arm 182. This face cam 196 has a projection 196^a which once in every revolution imparts movement to the rock arm 182 and the clutch actuating block 189 and feeler finger 165 which are connected thereto through the mechanism described. Said face cam 196 is keyed to the constantly running shaft 136 above referred to. The purpose of this automatic clutch controlling mechanism will be hereinafter explained in connection with the description of the operation of the entire machine.

It will be understood that any suitable delivery mechanism may be provided for taking the stapled pamphlets from the delivery end of the feed table.

In the operation of the machine, the operator stands at the left of the machine as shown in Fig. 2 where he can conveniently reach the foot lever 10 which shifts the power belt. The folded signatures or bunches of sheets to be formed into pamphlets are placed upon the angular table or saddle against the stationary gage 45, in which position they will be in reach of the first of the series of feed fingers 55. As the machine operates, each of the feed fingers 55 and the coöperating feed strip 65 are moved to the left with the feed fingers elevated and as the signature is put in place, the feed fingers are depressed into engagement with the signature and are moved to the right simultaneously with the feed strip 65, the feed fingers gripping the signature against the strip. This operation of the feed fingers and feed strip is accomplished through the oscillating bell crank 76 mounted upon the plate 70, the first movement of the bell crank upon the pivot causing the rocking of the shaft 50 which carries the feed fingers 55, and the final movement of the bell crank by its engagement with one of the limiting stops 80 causing the reciprocation of the plate 70, feed strip 65 and shaft 50 carrying feed fingers 55. By this feeding mechanism, the signatures are fed in a step by step manner through the machine, the feed fingers en- 130

gaging the signatures successively as they slide forward upon the feed table, and the operator placing a new signature in starting position as each signature is fed forward. By the trip clutch arrangement between the stapling machine proper and the shaft 136, the clutch is disengaged so as to retain the stapling machine at rest so long as there is no pamphlet in place to be stapled, this being accomplished by the tripping finger 161 resting by gravity in vertical position and intermittently preventing the movement of the feeler 165, which through the trip mechanism connecting said feeler with the clutch actuating block 189, prevents the withdrawal of the block from the path of the clutch hook, so that the clutch is held in disengaged position. When a signature or bunch of sheets reaches stapling position, the tripping finger 161 will be moved out of the path of the feeler 165 so that the spring 197 will be permitted to withdraw the cam block 189 out of the path of the clutch hook, with the result that the clutch will be engaged and the stapling machine will be operated to apply staples to the signature or bunch of sheets resting in position. The purpose of the cam 196 is to intermittently relieve the tripper 161 from the pressure of the feeler 165 so as to permit the movement of a signature into stapling position to actuate the tripper.

In Fig. 9 of the drawings, I have represented a succession of signatures or bunches of sheets in the position they assume as they are fed along the feed table. With the size of pamphlet illustrated in this figure, it is usual to insert only two staples. In Fig. 10 of the drawings, I have shown diagrammatically a longer pamphlet; with which it is desirable to insert a greater number of staples. In this latter case, my machine can be conveniently used by imparting feeding strokes of such length that each pamphlet will remain in stapling position during two feeding strokes, so that it will receive two staples in its leading end and two staples in its following end.

My invention provides an automatic machine by which pamphlets and the like are completely bound and covered in one operation without the necessity of any manipulation after the placing of the bunch of folded sheets or signatures in starting position upon the table in reach of the feed fingers.

What I claim is:

1. In a machine of the character described, the combination of a feed table, a reciprocatory rock shaft journaled adjacent to said table, means for imparting reciprocating and rocking motions to said rock shaft, a reciprocatory feed slide mounted upon said

table, and a series of fingers mounted upon said rock shaft and adapted to intermittently and successively engage sheets against said feed slide for feeding them step by step upon said table.

2. In a machine of the character described, the combination of a feed table, an automatic stapling machine mounted in operative relation to said feed table, a reciprocatory rock shaft journaled adjacent to said table, means for imparting reciprocating and rocking motions to said rock shaft, a reciprocatory feed slide mounted upon said table, and a series of fingers mounted upon said rock shaft and adapted to intermittently and successively engage sheets against said feed slide for feeding them step by step upon said table.

3. In a machine of the character described, the combination of a slotted feed table with a feed slide reciprocating in the slot of said table, a reciprocatory rock shaft journaled upon said table, feed fingers mounted upon said rock shaft in operative relation to said feed slide, a plate connected with said feed slide and shaft, stops upon said plate, a bell crank lever pivoted upon said plate, a connection between said bell crank lever and said rock shaft, and a reciprocating operating member connected with said bell crank lever.

4. In a machine of the character described, the combination of a feed table, a feed slide mounted to reciprocate upon said table, a reciprocatory rock shaft mounted upon said table, feed fingers carried by said shaft, a bell crank lever having crank connection with said shaft, a reciprocating plate connected with said feed slide and said shaft, a pivot upon said plate for said bell crank lever, adjustable stops carried by said plate to limit the movement of said bell crank lever, and a reciprocating operating member connected with said bell crank lever.

5. In a machine of the character described, the combination of a feed table, a feed slide mounted to reciprocate upon said table, a reciprocatory rock shaft mounted upon said table, feed fingers carried by said shaft, a bell crank lever having crank connection with said shaft, a reciprocating plate connected with said feed slide, an arm projecting from said plate and having pivotal connection with said shaft, a pivot upon said plate for said bell crank lever, adjustable stops carried by said plate to limit the movement of said bell crank lever, and a reciprocating operating member connected with said bell crank lever.
